METHOD OF DETERMINING MANGANESE IN
THE PRESENCE OF IRON

William D. Brown, Pittsburgh, Pa.

No Drawing. Application September 3, 1941,
Serial No. 409,429

2 Claims. (Cl. 23—230)

The problem of the quantitative determination of manganese in materials which contain large amounts of iron has received considerable attention and a number of methods have been devised for accomplishing a quantitative separation of these elements and the determination thereof, which methods are open to various objections. The object of the present invention may be said to be generally to provide of a rapid method for accurately determining the manganese content of manganese-rich materials, which may be high in iron, such as manganese ores, ferro-manganese or the like, the object of the invention having for a more specific object the provision of a method for the volumetric determination of manganese in such materials as have been mentioned above, which method combines speed and accuracy.

It is customary in prior methods for determining manganese to oxidize the manganese to permanganic acid which then is titrated with a standard solution of ferrous sulphate.

Among other objections, the prior methods are rather slow and the amount of manganese that can be determined is small, on account of the small samples that are required to be used and the rather large volume of solutions which must be handled before the completion of the determinations involved. In accordance with the present invention, a larger sample of material may be employed, with more accurate results, than has been possible heretofore.

The process of the present invention is based upon the oxidation of manganese by perchloric acid and phosphoric acid, the oxidation resulting in a bright purple solution in which the manganese may be determined as described herein-after. The manganese in this solution is present as Mn_2O_3 .

During this oxidation with perchloric acid, some free chlorine is formed which must be removed. In view of the fact that if the aforesaid purple solution is diluted and boiled for the removal of chlorine, the solution is decomposed and rendered unfit for the determination; to avoid this, the chlorine is removed preferably by blowing air through the solution until the air has carried out all free chlorine. Any small trace of hydrochloric acid is precipitated by silver nitrate.

In carrying out the process the following detailed procedure is employed.

A sample of 0.5 to 1 gm. is weighed accurately and transferred to a tall 300 ml. beaker.

For a ferro-manganese sample add 10 ml. of concentrated hydrochloric acid and 35 ml. of

perchloric acid (55%). The resulting mixture is heated to dissolve the sample after which 20 ml. of phosphoric acid (85%) are added.

For ores, 25 ml. of hydrochloric acid are added and the mixture heated until the sample is dissolved, which requires about half an hour. Then add 35 ml. of perchloric acid (55%) and 20 ml. of phosphoric acid.

The resulting solution from either type of material is boiled until the hydrochloric acid is boiled out. The beaker containing the solution then is heated while covered until perchloric acid fumes condense on the walls of the covered beaker and run down the sides. In the case of ferro-manganese, any carbon should be washed down by the fuming perchloric acid, and the heating is continued for about 10 minutes at a preferably lower temperature on a hot plate, the perchloric acid still fuming and condensing on the sides of the beaker.

The beaker is removed and allowed to cool in the air for $\frac{1}{2}$ minute and then cooled in water. Add 15 ml. of dilute sulphuric acid (1:1). For driving off the chlorine which is formed, washed air is passed through the solution while it is cooling, which requires about 20 minutes. Then, 10 drops of silver nitrate solution (0.5%) are added, followed by an addition of about 40 ml. of water.

The solution now is ready for titration. Add from an automatic pipette 100 ml. of ferrous sulphate solution. Add 2 ml. of phenanthroline ferrous perchlorate as an indicator and titrate with permanganate to the disappearance of the red color of the indicator. If desired, titration may be carried to the permanganate color.

For the titration of ferrous sulphate, add to a beaker 100 ml. of water, 10 ml. perchloric acid, 7 ml. phosphoric acid and 10 drops of silver nitrate solution. To this mixture, add 50 ml. potassium permanganate and then 100 ml. ferrous sulphate. After adding the indicator, titrate with potassium permanganate to the disappearance of the red color of the indicator. The potassium permanganate solution of course has been standardized.

The number of ml. of permanganate used in the test are deducted from the quantity used in the above-described "blank." The difference represents manganese. If a factor weight has been used, the readings will equal percentage of manganese.

As has been indicated above, the oxidation product of the manganese is Mn_2O_3 ; i. e., 2 atoms of manganese are combined with one extra

oxygen atom which is equivalent to 2 atoms of hydrogen. Since a normal solution of potassium permanganate contains 54.93 gms. of manganese per liter, the value of the permanganate in this titration per mil. then is 0.05493 multiplied by the normality of the potassium permanganate.

If a factor weight is not used the percent of manganese is represented by the mathematical formula:

$$\frac{100 \times 0.05493 \times \text{normality of permanganate} \times \text{ml. of permanganate}}{\text{Wt. of sample}}$$

For the preparation of the ferrous sulphate solution, 30 gms. of ferrous sulphate ($\text{FeSO}_4 \cdot 7\text{H}_2\text{O}$) or 42 gms. of ferrous ammonium sulphate ($\text{FeSO}_4 \cdot (\text{NH}_4)_2\text{SO}_4 \cdot 12\text{H}_2\text{O}$) are weighed out and dissolved in 1 liter of water containing 35 ml. of perchloric acid (55%) or 50 ml. of sulphuric acid.

If desired, the final titration may be carried out potentiometrically in accordance with the usual practice.

I claim:

1. A method of determining manganese in manganese-rich materials, which comprises dissolving a weighed sample of the material in hydrochloric acid, removing the hydrochloric acid from the resulting solution, oxidizing the manganese in the solution by perchloric acid in the

presence of phosphoric acid, removing free chlorine from the resulting solution by blowing air therethrough, adding to the solution measured volumes of standard ferrous sulphate solution in amounts somewhat in excess of the amount required to react completely with the manganese, and titrating excess ferrous sulphate with potassium permanganate in the presence of orthophenanthroline ferrous perchlorate as an indicator.

2. A method of determining manganese in manganese-rich materials, which comprises dissolving a weighed sample of the material in hydrochloric acid, removing the hydrochloric acid from the resulting solution, oxidizing the manganese in the solution by perchloric acid in the presence of phosphoric acid, removing free chlorine from the resulting solution by blowing air therethrough, adding to the solution measured volumes of standard ferrous sulphate solution in amounts somewhat in excess of the amount required to react completely with the manganese, and titrating excess ferrous sulphate with potassium permanganate until the titration reaches its end point.

WILLIAM D. BROWN.
